UNITED STATES PATENT OFFICE

AMOS P. STEINER, OF WAYNESBORO, PENNSYLVANIA, ASSIGNOR TO LANDIS TOOL COMPANY, OF WAYNESBORO, PENNSYLVANIA, A CORPORATION OF PENNSYLVANIA

INTERNAL-GRINDING MACHINE

Application filed August 17, 1925. Serial No. 50,779.

My said invention relates to an automatic sizing device for internal grinding machines and it is an object of the same to provide automatic means whereby a grinding machine 5 may be so controlled as to reduce hollow work to exactly the size desired, all without the attention or assistance of the operator.

Another object is to provide means whereby the work carriage is caused automatically to travel away or be withdrawn from the wheel when the work has been ground to the desired size.

Another object is to provide in a device of this character a circuit with a circuit breaker 15 having electrical contacts which when open are widely separated, but which move very quickly in closing the circuit, thus eliminating the usual slow-moving contacts that burn and fuse the contact points and so tend to make the device inaccurate.

Another object is to provide means whereby a work contacting finger is moved in radially from its feeling position as soon as the work is about to be withdrawn from the wheel.

Another object is to provide means whereby the work contacting finger is returned to the feeling position and the latch for the circuit breaker is returned to a closed position after the wheel enters the work to 50 grind the newly inserted piece of work.

Another object is to provide means whereby a wheel dressing device is automatically thrown around into operating position against the wheel while the work is in a withdrawn position, thereby enabling the wheel dressing operation to be performed automatically without loss of time as the work-holder carriage retreats and then advances to the operating position.

Referring to the accompanying drawings, which are made a part hereof and on which similar reference characters indicate similar parts,

Figure 1 is a front elevation of the sizing feeler mechanism withdrawal pawl and electromagnet therefor,

Figure 2, a side elevation of said device when viewed from the right of Figure 1,

Figure 3, a plan of the sizing feeler,

Figure 4, a plan view of the sizing feeler, partly in section,

Figure 5, a side elevation of said device viewed from the right of Figure 3 or Figure 4,

55

Figure 6, an enlarged end view from the left showing the grinding wheel and the work contacting finger in position in the work,

Figure 7, an enlarged front elevation of the work contacting finger, and

60

Figure 8, an enlarged plan view showing the wheel dresser and operating means thereof.

In the drawings (Figs. 1 and 2) reference character 10 indicates a bed or frame, 11 a work supporting carriage mounted to slide in guides 12, 10' an oscillating fluid motor driving a pinion 11' contacting with a rack 12' on the work carriage 11 for moving the work carriage into and out of contact with the 70 grinding wheel, and 13 a wheel carriage mounted in guides 14 for reciprocation of the grinding wheel 15 for grinding short articles all of which parts are or may be of the same design as is fully shown and described in my 75 previous application for a "selective internal grinding machine" No. 26,232, filed April 27, 1925. The various features of this device are shown as applied to a machine having the selective traverse features, but it will be obvious that my improvements may be applied to any internal grinding machine having either the traversing work or the traversing wheel methods of reciprocation, and it is my 80 intention so to apply them.

A supporting or bridge casting 16 is securely fastened at each end to the frame 10 in such a manner that the work carriage 11 may be free to pass under said bridge.

Mounted upon the bridge 16 is the base 17 of the sizing device said base being mounted for adjustment lengthwise of the machine, i. e. crosswise of the bridge 16, comprising a slot 17' and a clamping screw 18 (Fig. 1) such adjustment providing means for locating the sizing device in accordance with the length of the work.

A casing 19 is mounted on the base, said casing being adapted to slide upon the guides 20 toward or away from the work to suit ya, 100

riations in the diameter of the work. The casing is moved by means of an adjusting screw 21 which has a graduated dial 22 upon which the movement of the casing may be read in thousandths.

A work contacting finger 23 having a diamond point 24 for engaging the surface of the work 25 (Figs. 4, 5, 6, 7) is mounted for pivotal movement upon a vertical shaft 26, said shaft being supported by two bearings 27' (Fig. 5) which are in turn supported by the casing 19. Located on the shaft 26 between the two bearings is a forwardly extending arm 27 (Fig. 4), which is limited in its movement in one direction by the stop screw 28 and which holds the diamond 24 in engagement with the work 25 by the action of a spring 29.

A hardened block 30 has a stem inserted in a hole in the free end of arm 27 and this block is shaped in section as a right-angled triangle, with a forward edge between a flat face and the inclined face defined by the hypotenuse of the triangle. The block 30 engages with its end face the adjacent face of a block 31 mounted on the circuit closer arm 32, the arm 27 holds the arm 32 in an inoperative position but as the finished size of the work is approached the said arm 27 is rotated by the spring 29. This movement is controlled by the feeler arm 23 in engagement with the work 25. The device has been set as described above so that when the work has been ground to the desired size the arm 27 will have rotated far enough to release the arm 32. Preferably the tips of these faces are ground off to provide small flats which permits the parts to disengage suddenly and completely when the feeler finger 23 has moved out far enough, i. e. when the work is finished. The arm 32 is mounted on a shaft 33 and supported by two bearings 34, which are in turn supported by the casing 19.

Mounted upon the arm 32 is a contact 35 adapted to engage contacts 35' to close a circuit indicated diagrammatically in Figures 3 and 4. A spring 36 connected at opposite ends respectively to the arm 32 and to the casing serves to move the contact 35 quickly into engagement with contacts 35'. The movement of the arm 27 is practically completed before the lever 32 starts to move, the only remaining movement being over against the stop screw 28 and that can not be accomplished until after the circuit has been closed at 35, 35', and the work has traversed away from the wheel so far that the diamond 24 is out of contact with the work, which then allows the arm 27 to move under the action of the spring 29 over against the screw 28.

An electromagnet 37 is energized upon the closing of the circuit by the circuit closer 35 and said electromagnet lifts the pawl 38 (Fig. 1) out of engagement with the reversing lever 39, for the withdrawal movement, where the

pawl has been held to arrest the withdrawal mechanism. The lower end 39' of the reversing lever 39 has a roller 40' which rides upon an abutment 41'. It will be observed that the abutment has an inverted V-shaped end. The abutment 41' is urged upwardly against the roller 40' by a spring 42'. This reversing lever and abutment mechanism is of well-known construction as, for example, in Landis 639,900, 820,801 and Stoner 1,533,047. The reversing lever 39 is operated by dogs upon the work carriage in a manner well-known in the art and will not be further described herein. The patents to Landis above referred to are examples of such structure. Lifting of the pawl permits the withdrawal mechanism to become operative and withdraw the work 25 away from the grinding wheel 15 as for changing the work.

The shaft 26 has an arm 40 fixed thereto at its end said arm being provided with a roller 45 for engagement with a cam 47 on a cam bar 42 at the front edge of the work carriage and the shaft 33 has an arm 41 provided with a roller 44 for engagement with a cam 46 on a cam bar 43 similarly located. These cam bars participate in the withdrawal movement, are pulled through in under the bridge by this movement and are, of course, attached to the carriage 11 which supports the work holder.

A wheel dresser base 48 is mounted for swiveling movement on the bridge 16 back of the grinding wheel 15. The wheel dresser base has a shaft 49 extending through the bridge 16 and an arm 50 bearing a roller 51 is secured to the lower end of said shaft. A bar or screw 52 is threaded in the upper end of the base 48 and a wheel dressing diamond 53 is mounted at one end of the bar in any convenient manner.

A spring 54 holds the device in a retracted position as shown in Fig. 8 when not in use. A cam 55, acting against the roller 51 when the work carriage 11 withdraws from the wheel, swings the wheel dressing device around into the position shown in dotted lines, so that the travel of the wheel and the wheel carriage 13 will pass the wheel back and forth past the diamond, truing the wheel to proper condition for operation on the next piece of work.

In operation the work 25 being in operative position with the grinding wheel 15 grinding out the bore as shown in Fig. 4, the diamond 24 moves radially outward as the bore increases in size, the arms 23 and 27 swinging as far as permitted by the diamond until the work is finished when the detent block 30 allows the block 31 on the switch arm 32 to pass closing the circuit by means of the contact 35, and energizing the electromagnet 37 which raises the pawl 38 and so permits the withdrawal mechanism to pull the work away from the grinding wheel. It

will be observed that in the operation of the device, the movement of the work carriage to the right as shown in Fig. 1 will move the reversing lever 39 to the position shown in Fig. 1 whereupon the lever 39 will be held in position by the member 38. At this time the abutment 42' positioned beneath the roller 40' on the lower end of the reversing lever will tend to urge the reversing lever in a direction to reverse the carriage. The lever, however, is held in the position shown in Fig. 1 at which position the carriage is inoperative. When pawl 38 has been raised the abutment 41' under the influence of spring 42' will throw the lever 39 to a position to reverse the carriage. The finished work may now be removed and another piece inserted.

As the work carriage withdraws from the wheel the cam 46 engages the roller 44 breaking the circuit of the electromagnet by removing contact 35 from contacts 35' and so allowing the pawl 38 to drop down to operating position to engage the reversing lever for the withdrawal movement when the carriage returns.

The cam 47 then engages the roller 45 returning the rockarms 40 and 23 and moving the diamond 24 out of contacting relation with the work 25, such movement being permitted by the relative sizes of the stone and the opening in the work (Fig. 6). This movement of the diamond must be sufficient to allow room for an unfinished piece of work to be placed in operative position, the unfinished piece, of course, having a smaller hole than the finished work.

The relation of the cams 46, 47 and their coacting arms 40 and 41 is such that on completion of the work the arm 41 is first operated to break the circuit and move the contact 35 to a safe distance from contacts 35' as well as to remove block 31 out of the way of block 30. Thereafter the roller 45 is engaged by the cam 47 and the arm 40 is swung to the left to lift the diamond 24 out of engagement with the work 25 and hold it in retracted position until a new piece of work is in grinding position relatively to the wheel 15. This action also moves the arm 27 to the left of the position indicated in Figure 4 against the tension of the spring 29 and brings the block 30 above the block 31.

On return to the grinding position the cam 47 first permits the return of rockarms 40, 27 and 23 under the action of the spring 29 to a position determined by the internal diameter of the work 25. Thereafter the cam 46 permits the rockarms 41 and 32 to return under tension of the spring 36 to a point determined by the position of the block 30, the block 31 striking against block 30 and thus preventing engagement of the contacts of the circuit closer.

Upon completion of a piece of work the

worktable 11, as hereinbefore explained, moves to the left carrying with it the cams 46 and 47 which are attached thereto. The cam 55 also travels with the worktable 11 at this time being also attached to the table 70 and after the work has been disengaged from the wheel the cam 55 engages the roller 51 thereby swinging the rockarms 50 and 48 from the solid line position in Fig. 8 to the dotted line position against the tension of 75 spring 54. This brings the wheel dressing device into the position indicated in dotted lines with the diamond 53 into position to contact with the wheel. In the machine here illustrated the wheel has a constant traversing movement and the travel of the work carriage into work replenishing position and back may be so regulated as to allow the operator to remove the finished work and insert a new piece of work or such travel can be 80 stopped at the end of the outward stroke at the option of the operator. This travel of the work carriage will also be sufficient in ordinary cases to permit the wheel dressing operation to be completed by the time the 85 work carriage returns with a new piece of work. The various details of time relation, etc. will of course be arranged in accordance with the nature of the particular grinding machine.

The unfinished piece of work having been positioned the work approaches the wheel and the wheel enters the work. As this takes place all three cams, 55, 47 and 46, move to the right as seen in Figures 4 and 8, the cam 55 returns to the position indicated in Figure 8 and the spring 54 returns the work dresser to the position indicated in full lines. Thereupon the wheel enters the work and the cam 47 permits the diamond 24 to engage the work after which the cam 46 allows the block 31 to latch up against the block 30. After the grinding wheel has removed sufficient material to bring the work to predetermined size the block 30 moves back enough to allow block 31 to pass closing the contact at 35 and repeating the entire withdrawal operation.

The work may be fed toward the wheel during the grinding operation or the wheel may be fed toward the work and this is done by conventional means well known to those skilled in the art.

In order to set this device to grinding work of a given diameter, a piece which has already been ground to exact size and checked by a micrometer, is placed in a chuck. The arm 23 is inserted in the work with diamond 24 in contact with the finished surface while the housing 19 is in a withdrawn position, that is, toward the operator; said housing is then moved toward the work by means of a knob 21. As this movement progresses, the spring 29 keeps the diamond 24 in contact with the work 25 so that the arms 23 and 27 are rotated in a counter-clockwise direction. The hous-

ing is moved until the arm 27 has rotated far enough to release the arm 32. At this point on the graduated dial 22 is a proper setting for the given diameter.

It will be obvious to those skilled in the art that various changes may be made in my device without departing from the spirit of the invention and therefore I do not limit myself to what is shown in the drawings and described in the specification but only as indicated in the appended claims.

Having thus fully described my said invention, what I claim as new and desire to secure by Letters Patent, is:

1. In a grinding machine, a work holding device, an abrading device, a carriage for one of said devices movable toward or from abrading proximity to the other means for moving said carriage, a feeler engaging the work, electrically operated means for controlling the withdrawal of the carriage, a pivoted circuit-closer biased to close an electric circuit for said last-named means, a trip for holding said circuit closer in open position, connections between the feeler and the trip for releasing said circuit closer, a cam movable by the carriage withdrawal movement for returning the circuit closer to open position, and a cam moved by the carriage for thereafter resetting the trip, substantially as set forth.

2. In a grinding machine a work holding device, an abrading device, a carriage for moving one of said devices to a non-abrading distance means for moving said carriage, a feeler adapted to be positioned within the work in engagement therewith, electrically operated means for controlling the withdrawal of the carriage to the remote position, a pivoted circuit-closer biased to close the electric circuit, a trip for holding said circuit-closer in open position, connections between the feeler and the trip for releasing said circuit-closer, means attached to the carriage for returning the circuit-closer to open position, and means attached to the carriage for thereafter resetting the trip, substantially as set forth.

3. In an internal grinding machine, abrading means, work holding means, means to move the workholding means with respect to the abrading means, and means for controlling said work moving means comprising a housing, a normally open electric circuit in said housing, an arm adapted to close said circuit, a second arm mounted in said housing and tending normally to prevent closing of said electric circuit, a third arm adapted to contact with a work piece and also to cooperate with said second arm, means to move said second arm to release said first arm, and means whereby said third arm controls the movement in the second arm so as to release the first arm when the desired size has been attained, and means operable by movement

of the work holding means for moving said third arm to position its work contacting end within the work as the work holding means moves to abrading position, substantially as set forth.

4. In an internal grinding machine, a work holding device, an abrading device, a carriage for one of said devices movable toward or from abrading proximity to the other, a driving mechanism for said carriage, a normally operative reversing lever for said mechanism, a pawl adapted to stop said lever in inoperative position, resilient means urging the lever to operative position, electrically operated means for controlling the withdrawal of the carriage comprising an electro-magnet operable to lift said pawl to allow the lever to move to operative position, a circuit closer, a trip to hold said circuit closer in open position, a feeler engaging the work, connections between the feeler and the trip for releasing said circuit closer, cams on the carriage operable on the withdrawal of the carriage to return the circuit closer to open position, and means whereby said cams reset the trip as the carriage moves toward the work, substantially as set forth.

In witness whereof I have hereunto set my hand at Waynesboro, Pennsylvania this twelfth day of August, A. D. nineteen hundred and twenty-five.

AMOS P. STEINER.
